UNITED STATES PATENT OFFICE.

ADAM PELLERIN, OF ST. FLORE, QUEBEC, CANADA.

BULL-SCREEN CLEANER.

1,275,299.

Specification of Letters Patent. Patented Aug. 13, 1918.

Application filed May 6, 1918. Serial No. 232,723.

To all whom it may concern:

Be it known that I, ADAM PELLERIN, a subject of the King of Great Britain, residing at St. Flore, Province of Quebec, 5 Canada, have invented certain new and useful Improvements in Bull-Screen Cleaners; and I do hereby declare that the following is a full, clear, and exact description of the invention, such as will enable others skilled in 10 the art to which it appertains to make and use the same.

The present invention relates to bull screens used for screening wood pulp in the manufacture of paper, and an object of the 15 present invention is to provide a cleaner for such devices whereby the screen will be automatically and thoroughly cleaned while the wood pulp is being screened.

With the above and other objects in view 20 which will hereinafter appear as the description continues, the invention consists of the novel features of construction, combination and formation of parts as will be herein-after more fully described and particularly 25 pointed out in the appended claims.

In the accompanying drawings has been shown a simple and preferred form of the invention, it being, however, understood that no limitation is necessarily made to the precise structural details herein exhibited, but the right is hereby reserved to any changes, alterations or modifications to which recourse may be had that come within the 30 scope of the claims without departing from 35 the spirit of the invention or sacrificing the efficiency of the same.

In the accompanying drawings:

Figure 1 is a vertical section through a bull screen having an embodiment of the 40 present invention applied thereto;

Fig. 2 is a horizontal section taken on the line 2—2 of Fig. 1;

Fig. 3 is a side elevation of the water controlling valve;

Fig. 4 is a similar view showing one of the partitions removed; and,

Fig. 5 is a vertical section through the valve.

Referring now more particularly to the 50 accompanying drawings wherein like and corresponding parts are designated by similar reference characters throughout the several views.

The numeral 1 indicates an ordinary bull 55 screen having a plurality of perforations 2 arranged in the bottom thereof which is of

the ordinary construction. Mounted above the screen 1 is a driving shaft 3 and this shaft has connected thereto a pulley 4 and the latter is adapted to be connected to a suitable motor power whereby the shaft will be rotated in the direction of the arrow as shown in Fig. 1 of the drawings. Keyed to this shaft 3 are a pair of spaced hubs 5 and each of these hubs have two arms 6 formed therewith and the arms carried by each hub extend diametrically opposite but at right angles to the arms carried by the adjacent hub. Pivotedly mounted as at 7 within the outer ends of these arms 6 are the levers 8 and these levers each carry a wiper 9. The opposite ends of the levers are connected to the arms 6 by means of the coil springs 10. While the shaft 3 is rotating the wipers 9 will be carried therewith and these wipers 75 will pass over the inner face of the screen 1, thereby clearing the wood pulp from the perforations 2. After these wipers have passed over the perforations 2 it is then desired to cleanse the openings or remove the 80 wood pulp contained therein by means of a suitable cleansing liquid such as water, and the wipers after passing over the screen should also be cleansed so as to remove any 85 wood pulp or cellulose adhered thereto. To supply this cleansing liquid to the screen and the wipers automatically and at the time desired, I provide the sprayers which are connected to a valve whereby the water or any other suitable cleansing material will 90 be supplied to the sprayers at the desired time.

Supported within the screen 1 is a transverse bar or support 11 and mounted upon this bar 11 is a valve. This valve comprises 95 a casing which consists of a lower stationary section 12 which is secured to the bar 11 by means of the bolts 13 and an upper or removable section 14 which is connected to the section 12 by means of the bolts or other suitable fastening members 15. These sections 12 and 13 have correspondingly inwardly projecting flanges 16 forming a compartment 17 therebetween and a suitable supply pipe 18 is in communication with 105 this compartment or channel way 17. Keyed to the shaft 3 is a hub having formed therewith a pair of spaced flanges or partitions 19 and these flanges 16 are adapted to rotate within the flanges 19. The sections 12 and 110 13 have embedded therein the copper rings 20 and the latter also project within grooves

formed within the flanges 19 so as to prevent the water from leaking from the valve. The flanges 16 formed with the section 12 have formed therein the elongated slots 21 and 22 and the rotatable flanges 19 have formed therein the openings 23 and 24 which are adapted to register with the respective slots 21 and 22. Communicating with each of the openings 23 is a pipe 25 having secured to its outer end a transversely extending perforated pipe or sprayer 26. The sprayers 26 are arranged in back of the wipers 9 as better shown in Fig. 1 and each of the pipes 25 are provided with a flexible portion 27, so that the sprayers 26 may pass freely over the inner face of the screen 1. Communicating with each of the openings 24 is a pipe 28 and each of these pipes have formed with their outer ends a transversely extending perforated pipe or sprayer 29. These sprayers 29 are arranged in front of the wipers 9 so as to clean the wipers after they have left the wood pulp contained within the screen.

25. The operation of the device is as follows: As the shaft 3 is rotated the arms 6 will be carried therewith and as the respective wipers 9 contact with the inner face of the screen they will clean or remove the wood pulp from the openings 2. As each opening 23 registers with the slot 21 water will be supplied to the pipes 29 and in turn the sprayers 26 will be set for a spray of water which will clean the openings 2 after the wipers 9 have passed over these openings. The slots 21 are so arranged that the openings 23 will only communicate therewith when the sprayers 26 are passing over the inner face of the screen 1, but as the wipers 9 leave the screen the water will be cut off from the sprayers 26 until it again passes within the screen. When one of the wipers 9 has assumed the position of the wiper as shown at the right hand side of Fig. 1, it will be free of the wood pulp but a portion of the wood pulp or cellulose will adhere to the wipers as they pass through the wood pulp, and as the wipers assume this position the pipes 28 will be brought in communication with the slots 22 wherein the water will be permitted to travel to the sprayers 29 and these sprayers will then exert a spray of water upon the wipers whereby they will

be free of wood pulp before leaving the screen.

Having thus fully described my invention, what I claim as new and desire to secure by Letters Patent is:

1. In a bull screen cleaner the combination of a screen, a driving shaft mounted above said screen, wipers carried by said shaft and adapted to contact with said screen, and sprayers arranged in front and in the back of each of said wipers substantially as and for the purpose specified.

2. The combination with a bull screen, of a rotatable shaft mounted thereupon, wipers carried by said shaft and adapted to contact with said screen, a supply pipe, a valve arranged within said supply pipe, sprayers carried by said shaft and in communication with said supply pipe, and said shaft adapted to operate said valve substantially as and for the purpose specified.

3. The combination with a bull screen having a plurality of perforations therein, of a driven shaft mounted above said screen, a plurality of arms carried by said shaft, a wiper carried by each of said arms and adapted to contact with said screen, sprayers carried by said shaft and arranged adjacent to said wipers, a supply pipe communicating with said sprayers, a valve arranged within said supply pipe, and said shaft being operatively connected to said valve.

4. The combination with a bull screen, of a driven shaft mounted above said bull screen, a plurality of arms carried by said shaft, a flexible wiper carried by the outer end of each of said arms, said wipers adapted to contact with said screen, sprayers carried by said shaft and adapted to rest adjacent said wipers, a supply pipe, a rotatable valve arranged within said supply pipe, means for operatively connecting said valve with said shaft, said sprayers being in communication with said supply pipe and means whereby upon the rotation of said shaft said valve will be opened and closed for supplying water to said sprayers substantially as and for the purpose set forth.

In witness whereof I have hereunto set my hand.

ADAM PELLERIN.
